CLAIM

The ornamental design for a road surface clearing apparatus, as shown and described.

DESCRIPTION

FIG. 1 is a perspective view of a road surface clearing apparatus according to my new design;

FIG. 2 is a back elevation view thereof;

FIG. 3 is a front elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a perspective view of another embodiment of a road surface clearing apparatus according to my new design;

FIG. 9 is a back elevation view thereof;

FIG. 10 is a front elevation view thereof;

FIG. 11 is a top plan view thereof;

FIG. 12 is a bottom plan view thereof;

FIG. 13 is a right side elevation view thereof; and,

FIG. 14 is a left side elevation view thereof.

The broken lines are directed to environment and are for illustrative purposes only. The broken lines form no part of any embodiment of the claimed design.

1 Claim, 14 Drawing Sheets
